UNITED STATES PATENT OFFICE.

JAY G. SWAB, OF BROOKLYN, NEW YORK, ASSIGNOR TO HENRY TRENCHARD, JR., OF NEW YORK, N. Y.

REENFORCEMENT-APPLYING MECHANISM.

Application filed May 5, 1923. Serial No. 636,808.

To all whom it may concern:

Be it known that I, JAY G. SWAB, a citizen of the United States, and resident of New York city, borough of Brooklyn, county of 5 Kings, State of New York, have invented an Improvement in Reenforcement-Applying Mechanism, of which the following is a specification.

The present invention relates to apparatus for use in the manufacture of envelopes and more particularly to a device for applying reenforcement to the envelope blank during the manufacture of the envelope.

15 Envelopes of certain types are provided with cooperating fastening devices for holding the flaps in closed relation. Such fastening devices may comprise cooperating elements one of which is attached to the flap and the other to the body of the envelope, a string being secured to one and being arranged for engagement with the other, or they may comprise a metal fastener permanently secured to the body of the envelope 20 and arranged to engage a reenforced hole in the flap in such manner as to secure the same in closed relation. In order to prevent the fastener from tearing out of the envelope and also in order to hold the fastener in 25 rigid position in use in case a metallic fastener of bendable material is employed, it is desirable to reenforce the envelope at the point where the fastener is secured thereto as by means of a reenforcing patch. If the 30 reenforcement lies on the outside it presents a more or less unsightly appearance. If it lies on the inside of the envelope it tends to interfere with the insertion of papers by catching the edges thereof.

35 The present invention has for an object to provide improved means for applying reenforcement and one which will be reliable and economical in operation.

The invention has also for an object to 40 provide means whereby the reenforcement may be applied during the manufacture of the envelope so that in the finished article it will lie within the seam.

45 The nature and objects of the invention 50 will be better understood from a description of a selected illustrative embodiment thereof. For the purpose of such description,

reference should be had to the accompanying drawings forming a part hereof.

Figure 1 is a side view of reenforcement 55 applying mechanism constructed in accordance with and embodying the principles of the invention.

Figure 2 is a plan view of a sectional conveyor roll.

Figure 3 is a detail view of the reenforcement severing blade.

Figure 4 is a detail view of the gripper operating cam.

Figure 5 is a diagrammatic view showing 65 the relation of the reenforcement applying mechanism to the envelope folding mechanism, a merely conventional folding mechanism being indicated.

In the apparatus shown for the purpose 70 of illustration, the reenforcement is applied to the envelope blank while it is held in position on a conveyor roll 5. The reenforcement may be fed to applying position in any suitable manner. As shown the reenforcement is in the form of a continuous tape 6 supplied in a roll 7 from which it is drawn as required.

75 The reenforcement may be affixed to the blank in any suitable manner. In the 80 arrangement shown, paste or other adhesive is applied to the blank during its travel through the machine along the line of the proposed seam and the reenforcement which may be plain material without gum or paste, 85 is secured to the blank by this paste, after which additional paste preferably is applied to the exterior of the reenforcement in order that the seam may be continuous when the blank is folded to form an envelope.

90 The apparatus illustrated is designed for use in the manufacture of envelopes of the type wherein a blank having parallel side edges is folded to tubular form, the extreme side edge portions of the blank constituting seam forming areas which are 95 overlapped and pasted together to form a central seam.

One seam forming area lies parallel and close to the edge of the roll 5 as shown in 100 Figure 1 and receives paste from a nozzle 10. The conveyor roll 5 may be of any suitable construction and may either be continuous or may be sectional. In Figure 2 a sectional

roll is shown. Two central laterally adjustable sections 11, 11 are provided with grippers 12, 12 engageable with the forward edge of the blank. Two side sections 13, 13 are 5 adjustable laterally to correspond to the width of the blank and circumferentially to adjust the position of the reenforcement applying device relative to the forward edge of the blank to determine the position of the 10 reenforcement on the blank.

In the arrangement shown, the strip of re-enforcing material is led through a guide 15 from which the end projects as indicated at 16 to be applied to the envelope blank. The 15 operation of the device is such that the re-enforcement material is fed step by step through this guide 15. During the interval between successive feeding movements a blade 18, is projected inwardly to partially 20 sever the strip. The blade is actuated from a cam 19 on the feed roll shaft through the levers 20, 21 and a connecting link 22. The blade 18 presents an interrupted edge as indicated in Figure 3, portions of the strip 25 being left uncut by the notched portions 23 of the blade, whereby the strip may be drawn forward to feed the same.

As a convenient means for affixing the re-enforcement to the envelope blank there is 30 shown a clamp or gripper member 25 pivotally mounted on the feed roll. This gripper has an outwardly extending arm 26 with a cam engaging roller 27 which is actuated by a stationary cam 28. The design of the 35 cam 28 is such that when, during the rotation of the conveyor roll 5, the gripper arrives opposite the projecting end 16 of the reenforcement strip it will move sharply inwardly and downwardly to press the reenforcement against the envelope blank carried by the conveyor roll. The continuing 40 rotation of the conveyor while the reenforcement is thus gripped causes the strip to be drawn through the guide or fed. As 45 shown the gripper cooperates with other devices not only to feed the strip but also to sever the affixed length of reinforcing material from said strip. In the structure 50 illustrated, the severing is accomplished by providing a clamp 30 for holding the strip momentarily at predetermined times. Upon 55 rotation of the clamp member a blade 31 grips the strip between itself and an anvil 32 on the guide. This clamp is provided with an upwardly extending arm 33 which is 60 actuated through a bell crank lever 34 one arm of which carries a roller 35 that is actuated by a cam 36 on the conveyor roll shaft. The operation of the clamp is timed to engage the strip just after a length equal 65 to the length of a single patch has been fed.

In operation the gripper 25 engages the 70 projecting end of the reenforcing strip and moves forward with the feed roll, thereby drawing out a predetermined length of the

reenforcing strip. When a length equal to the length of the individual patch has been withdrawn, the clamp 30 operates to hold the strip, the clamp being arranged to engage the section of the reenforcement next 70 behind that actually being applied. The pull of the clamp member upon the applied reenforcement then severs such applied reenforcement from the next following section, leaving such following section projecting in 75 position to be engaged by the clamp member upon the next succeeding patch applying operation. The gripper having completed its function is then returned by its cam 28 to its open position.

The envelope blank now presents a line of paste which is interrupted by the section of reenforcement applied thereto. In order that the pasted seam of the finished envelope may be continuous, paste is now applied to the exterior of the reenforcement by means of a paste applying device 40 which is operated to apply a limited quantity of paste to the exterior face of the patch only. This paste is applied as the blank passes forward over the guide ways 41. The flow of paste or other adhesive in the nozzles 10 and 40 may be controlled by suitable cam actuated valves as is known in the art. It is unnecessary to illustrate herein such control means in detail. It is indicated diagrammatically.

As the envelope blank with the reenforcement applied thereto passes forward to the envelope folding mechanism the side wings are folded laterally by the folding plates 44 and 45 to bring the side wings in overlapping relation with the reenforcement within the seam. The bottom flap of the envelope is then folded by the rolls 46 to complete the envelope as is usual in machines of 105 this character.

The apparatus shown is illustrative merely and should not be considered as defining the limits of the invention. Various modifications and other embodiments may be 110 made without departing from the spirit of the invention.

I claim:

1. In apparatus for use in the manufacture of envelopes, in combination means for affixing reenforcement to the blank at a predetermined point on a seam forming area and means for folding the blank to form an envelope with the affixed reenforcement within the seam.

2. In apparatus for use in the manufacture of envelopes, in combination means for affixing reenforcement to the blank at a predetermined point on a seam forming area, means for applying paste to the blank along the seam forming area and means for folding the blank to form an envelope with the affixed reenforcement within the seam.

3. In apparatus for use in the manufacture of envelopes, in combination conveyor

- means for carrying an envelope blank having paste applied to a limited area along one edge thereof, means for feeding reenforcement to a point in registry with a portion of said limited area, and means cooperating with the conveyor means for pressing the reenforcement against the blank within the limited area to affix the reenforcement to the blank.
- 10 4. In apparatus for use in the manufacture of envelopes, in combination conveyor means for carrying an envelope blank, means for supporting reenforcement in proximity to the path of the blank, means 70 cooperating with the conveyor means for affixing the reenforcement to the blank during the movement of the blank on the conveyor.
- 15 5. In apparatus for use in the manufacture of envelopes, in combination means for supplying and affixing a reenforcing patch to the envelope blank and means for applying paste to the exterior of the affixed patch.
- 20 6. In apparatus for use in the manufacture of envelopes, in combination a conveyor member for carrying an envelope blank, means for supplying reenforcement to a position adjacent said conveyor member,
- 25 30 a clamp carried by the conveyor member arranged to clamp a section of reenforcement against an envelope blank to affix it thereto during the movement of the conveyor member and to draw the reenforcement from 90 said supplying means.
- 35 7. In apparatus for use in the manufacture of envelopes, in combination conveyor means for carrying an envelope blank, means for feeding reenforcing patches successively to patch applying position adjacent the conveyor means, means for pressing a patch against an envelope blank during the feeding movement of said conveyor means to affix the patch to the envelope blank.
- 40 8. In apparatus for use in the manufacture of envelopes in combination means for conveying an envelope blank, means for guiding a reenforcing strip to a point adjacent the path of the envelope blank, means 100 for partially severing the reenforcing strip into predetermined lengths, means for clamping the free end of the reenforcing strip against the envelope blank during the conveying movement to affix a portion thereof to the envelope blank and to draw out a length of the strip, and means for clamping the reenforcing strip beyond a point of partial severing to cause severing of the strip by the envelope feed and clamping means.
- 45 9. In apparatus for use in the manufacture of envelopes, in combination a conveyor roll, a support for a reenforcing strip adjacent the conveyor, means for partially 110
- 50 10. In apparatus for use in the manufacture of envelopes, in combination, means for feeding an envelope blank, means for applying a line of paste to the blank during its feeding movement and means for affixing reenforcement to the blank at a predetermined point on said line during the feeding movement.
- 55 11. In apparatus for use in the manufacture of envelopes, in combination means for applying a line of paste to an envelope blank, means for affixing reenforcement to the blank at a predetermined point on said line, and means for folding the blank to 90 form an envelope.
- 60 12. In apparatus for use in the manufacture of envelopes, in combination means for applying a line of paste to an envelope blank, means for affixing reenforcement to the blank at a predetermined point on said line, and means for applying paste to the exterior of said reenforcement.
- 65 13. In apparatus for use in the manufacture of envelopes, in combination means for applying a line of paste to an envelope blank, means for affixing reenforcement to the blank at a predetermined point on said line, means for applying paste to the exterior of said reenforcement, and means for folding the blank to form an envelope with the reenforcement within a seam.
- 70 14. The combination with a conveyor roll for feeding an envelope blank of means for supplying reenforcement to a point adjacent the feeding roll, a clamp carried by the feeding roll engageable with the reenforcement to press the same against the envelope blank to affix it thereto, and a cam actuating said clamp.
- 75 15. In paper working apparatus in combination, means for feeding a blank, means for affixing reenforcement to the blank at a predetermined point on a seam forming area and means for folding the blank to bring the seam forming areas in overlapped relation to form a seam with the reenforcement within the seam.
- 80 16. In paper working apparatus in combination, means for supporting a blank having seam forming areas, means for applying paste along one seam forming area, means for affixing reenforcement to the blank at a predetermined point on one seam forming area and means for folding the blank 120
- 85 17. In paper working apparatus in combination, means for supporting a blank having seam forming areas, means for applying paste along one seam forming area, means for affixing reenforcement to the blank at a predetermined point on one seam forming area and means for folding the blank 130

to engage the seam forming areas to form the seam with the reenforcement within the seam.

17. In paper working apparatus in combination means for supporting paper having areas to be superposed, means for applying paste to one such area, means for affixing a reenforcement to a portion of one

of such areas and means for manipulating the paper to superpose such areas with the ¹⁰ reenforcement therebetween.

In testimony whereof, I have signed my name to this specification this 25th day of April, 1923.

JAY G. SWAB.
